PRODUCT FOR THE TREATMENT OF THE
ALIMENTARY CANAL

Mortimer Bye, Cincinnati, Ohio

No Drawing. Application November 15, 1934,
Serial No. 753,183

2 Claims. (Cl. 167—56)

It is estimated that perhaps 90% of the ills of humanity are occasioned directly or indirectly from disturbances of the intestinal tract.

Chronic or occasional constipation is prevalent among all races and all ages, and inasmuch as the lives of most people are becoming more and more sedentary, real exercise being more and more uncommon, the eating of rich foods at untimely hours, irregular and inadequate sleeping periods, and lack of habit in caring for bodily functions, all tend to the disturbing of normal digestive processes, wherefore it appears to be logical and reasonable to expect that this condition will become more and more prevalent.

Authoritative medical opinion is opposed to the promiscuous use of laxatives. In many cases of abdominal pain, laxatives are contra-indicated, and may produce fatal results. Nevertheless, there are numerous laxative products offered for sale and it is to be expected that the public will be offered this type of product, and that millions of dollars will be spent annually by the public on products of this character, until and unless some real solution is presented.

Mineral oil, while not acting as a laxative, is, however, recognized as one of the safest agents for relieving to some extent, the condition of chronic or occasional constipation. Mineral oil, or emulsions of such oils exert their actions simply as lubricants. These exhibit no therapeutic effect and do not increase peristaltic action. In other words, they do not spur up the intestinal musculatures to excessive activity, and therefore do not produce the harmful effects which might be caused by laxative agents of a drastic physiological nature. However, the present method of administering mineral oil or emulsions of the same, is not a rational one, nor does such administration produce the best results. Usually the patient takes a dose of mineral oil at night before retiring expecting this to mix with the contents of the intestinal tract, thereby permitting of greater ease of evacuation. Disappointing results are bound to occur frequently, and the reason for such disappointments may be due in part to the fact that during the daytime hours, meals have been eaten, digestive processes have been working at maximum activity, and waste products of digestion have been accumulating and packing in the intestinal tract. In the case of individuals who are subject to constipation, this waste tends to form into hard compact masses, difficult of expulsion from the body. Severe pain often ac-

companies such expulsion. To overcome this condition, mineral oil is taken with the thought that the oil will mix with these masses, and that it will stimulate ease of bowel movement. These results fail to occur frequently. The mineral oil, taken at night, when the body functions are most nearly at rest, tends to seep through the intestines instead of mixing with the intestinal contents. Lubrication effects produced are chiefly surface lubrication effects, and the one function of the oil is so restricted that it may prove of doubtful value. That the oil seeps through the intestines and around the masses is recognized by all users of mineral oil, and by all who are familiar with the highly objectionable "leakage" which cannot be controlled.

The logical way to administer such oil would be to take it during and shortly after meals, and on retiring, in relatively small amounts. Such a method would insure that during the processes of digestion, namely, at the most active periods of our daily work, this oil would be intimately mixed with the contents of the intestines at all times. Such oil-containing matter would not tend to pack in hard masses, ease of evacuation would increase, nature would not be compelled to expel toxin-containing matter at the expense of increased and unnecessary body functions, and the danger of seepage would be more adequately controlled. Such method of administration of the oil would be an unpleasant and bothersome task for most all of us who would use that substance, and would be an almost impossible task for most of those who would wish to use mineral oil.

In order to obviate cases of constipation, either chronic or otherwise, it is desirable to encourage peristalsis of the intestines. In order to accomplish this and in order to obtain a normal and easy functioning of the intestinal tract, it is desirable that a considerable mass of substance to be worked on, be supplied to the intestines, and that this material or substance being worked on in the intestines, shall have the faculty or power of absorbing moisture. In view of the difficulties previously enumerated and in connection with the work that I have done in seeking to solve in a simple and easy manner, the situation as confronts the large majority of humans, I have discovered and absolutely established that by producing a wafer or cake-like product comprising agar-agar and mineral oil, I attained excellent results, and, moreover, such

product is highly effective for effecting normal intestinal condition and action.

It is preferred that in producing a wafer or cookie comprising agar-agar and mineral oil, that some binder such as flour be admixed therewith, and that suitable flavoring matter be also employed. A cake, wafer, or tablet produced of substance of the character indicated, may be eaten as part of an ordinary meal or immediately thereafter, thereby obtaining an intermixing of the product or composition with the food, as it passes through the intestine. During that period there would be a gradual breaking down of the structure of the cake or tablet due to the digestive processes, whereby there would be a gradual liberation of the mineral oil which would be admixed throughout the fecal matter that would prevent the compacting previously referred to and which compacting is essentially a condition common to constipation. Moreover, the effect of the body heat while the cookie or tablet is in the intestines would likewise assist in gradual liberation of the oil from the agar-agar or other oil of like character, with the result that as the oil is liberated from the agar-agar or similar material, there would be a moisture absorption which would create a swelling or expanding of the agar-agar or similar material, whereby to create a condition that medical science considers very desirable in the treatment of cases of chronic constipation and for producing a normal peristalsis and musculation. It is possible to regulate and control the size of the cakes or wafers, thereby making it possible for each person to readily determine what a proper dose is for his particular anatomical condition, that would give the most satisfactory results. The indicated gradual liberation of the oil in the intestines is occasioned by reason of the fact that particles of the wafer or cookie of appreciable size will pass through the stomach and only in the intestines will they be gradually disintegrated.

Instead of producing the composition of matter in the form of cakes, cookies, wafers or tablets, the product may be broken up so as to substantially resemble the cereals or so-called breakfast foods such as corn flakes and the like, and in such form the substance may be eaten with cream or fruit as is common with cereal foods of the character indicated.

The reference to cereals herein, is not limited to the so-called breakfast foods, but is intended also to indicate that flour obtained from various grains is generally referred to as a cereal product and as such, constitutes a suitable and satisfactory binder for producing units or integral wafer-like products. While I recognize the fact that there have been made heretofore emulsions comprising agar-agar and mineral oil, such preparations are not contemplated within the terms "unit" or "integral mass" as I use those terms herein. It is my intention to obviate the administration of emulsions and the like, of the character indicated, wherein dosage, ordinarily by means of spoons, is necessary and which method of administration is obnoxious or nauseating to many persons. Moreover, emulsions or administrations of mineral oils alone are not satisfactory because administration of mineral oil alone is attended by objectionable features and reactions previously mentioned and emulsions comprising mineral oil differ very little in their reactions because the oils separate very readily by reason of the fluid nature of such preparations, wherefore substantially the same body reactions

are obtained as are attained by the administration of mineral oil alone. Those emulsions previously referred to, comprising agar-agar and mineral oil are no different in this regard from any other emulsions comprising mineral oil. The apparently critical distinction between my invention and emulsions comprising agar-agar and mineral oil is that the period necessary for separation of the mineral oil from the agar-agar and other substances that are used in producing the product of the invention precludes accumulation of quantities of mineral oil that will seep through and from the intestines. Instead, as the minute particles of mineral oil are released from my product, such particles are so intimately associated as small minute particles, with the fecal matter in the intestine and with the agar-agar or like material which gradually swells by reason of the absorption of water of digestive juices and/or fluids, found in the intestinal tract, that the formation of bodies of mineral oil, even though of comparatively small size, is precluded. The result is that effective lubrication of the intestinal walls, as well as of the fecal matter itself, is attained, thereby obviating constipation or conditions approximating constipation.

In some instances the condition of a patient may be such that some cathartic or laxative reaction is necessary. My invention therefore contemplates that there may be admixed with my composition matter heretofore described, suitable laxative, for example, phenolphthalein. A product comprising such laxative would ordinarily be utilized in connection with acute cases of constipation and aggravated cases of chronic constipation, the laxative agent serving to initiate the abnormal condition of peristalsis previously referred to in order to effect evacuation of the impacted masses previously formed in the intestines. While ordinarily the use of laxatives accomplishes first, an abnormal peristalsis or intestinal musculation which might be termed excessive activity, and it is to be therefore expected that such period of excessive activity will be followed by a period of subnormal activity, during such period of subnormal activity, it is to be expected that a process of impacting or compacting will follow the condition of subnormal intestinal activity. Following administration of my said product, there will not result an intestinal condition that is as severe or objectionable as would follow cases where ordinary laxatives will be used, because the minute particles of mineral oil distributed throughout the fecal matter that is formed after the impacted masses are advanced by reason of the use of my product, prevents the fecal matter from assuming the condition of hardness that results in ordinary cases of chronic constipation. After a period of time, the product containing a laxative may be totally discontinued and then my product, free of laxative, is utilized for attaining and maintaining normal peristalsis and intestinal musculation.

While I have referred herein to mineral oil, it is to be understood that I do not intend to limit the term to any one of the various so-called mineral oils that medical science has found efficacious and suitable for internal administration to humans and also by reference to agar-agar, it is not intended to limit the product to one comprising agar-agar as the sole carrier of the mineral oils. Agar-agar is referred to herein because it is typical of a number of substances including psyllium seed, which have the faculty of absorbing and expanding or swelling in the pres-

ence of fluids such as water or water-containing fluids. My invention is therefore to be understood as contemplating that the composition of my invention comprises a mineral oil, a substance of the class of agar-agar and/or psyllium seed having the ability to carry mineral oil and to release the same under the influence of the digestive processes of the human body, together with a suitable binder, of mucilaginous or like character, for example, flour, or some glutinous component of flour, that will not interfere with, but will respond to the digestive processes of the stomach so as to gradually disintegrate and to thereby release the agar-agar or like material, to the digestive fluids so that the mineral oil may in turn be gradually released so that the fluids of the stomach may in turn be absorbed by the agar-agar or like material.

While I have referred to agar-agar and psyllium seed as examples of substances that may be used, it is intended to make evident and clear that other substances of like characteristics may be used, I prefer using agar-agar because both agar-agar and mineral oil have no physiological action on the intestines. Laxatives generally do have a physiological action, namely, laxatives create more than normal activity of the intestines resulting in evacuation to some extent, followed by periods of subnormal activity, during which periods of subnormal activity the constipational condition is recreated. Psyllium seed has a mild laxative effect and for this reason I consider agar-agar preferable, except that in the form of my invention where a laxative agent is desired, and in connection with which I mentioned the use of a phenolphthalein, or other laxative, it might be desirable to use psyllium seed in preference to agar-agar. The advantages of these various substances in view of these variant characteristics, are readily appreciated by the medical profession and to that extent it will be readily evident that these various substances are equivalents to a substantial degree or extent.

Some of the products that I have made and had made and embodying the invention comprise the following composition:

	Teaspoonfuls
Mineral oil	40
Agar-agar	40
50 Glucose	15
Sugar	13
Cocoa, powder	12
Salt, approximately	1/4
Flour	180
55 Vanilla extract	2

The indicated amounts of materials would be

mixed together for producing a dough-like substance and should make about forty cookies or tablets. These cookies or tablets are made by forming the dough-like substance in suitable bake pans or upon a suitable bake pan, and are baked in substantially the same way that bakery goods are treated.

By using the indicated amount of admixed substances to make forty cookies, it is obvious that each cookie will contain approximately one teaspoonful of mineral oil and one teaspoonful of agar-agar. These amounts would constitute an average dose that would be adequate lubrication for the ordinary person, assuming that one such cookie would be eaten during or after a meal. The cookies are tasty and palatable either eaten alone or with a meal.

In some instances I have used tapioca flour instead of the wheat flour referred to in the preceding formula. It would be readily obvious that oatmeal might likewise be used, and that by reason of the glutinous nature of the oatmeal, the use of any other binders might be obviated. It is therefore to be understood that in the appended claims insofar as there is specific reference to binders, it is to be understood that the inherent glutinous binder material that may be present in various cereals discloses that part of the appended claims calling for a binder.

The agar-agar and psyllium seed may be in any of various forms, for example, they may be pulverized, shredded or otherwise.

I found that the cookies or tablets made by me and which were made in accordance with the disclosures herein, present a very good appearance, withstand rough treatment, and do not deteriorate under varying climatic conditions. The products made according to the foregoing formula were free from oily appearance, as well as being free from oily taste.

What is claimed is:

1. A dry edible cookie comprising approximately equal parts of agar-agar and mineral oil, and a binder.

2. A baked dry edible product of substantially the following composition and proportions, viz:

	Parts
Mineral oil	40
Agar-agar	40
Glucose	15
Sugar	13
Cocoa.	12
Salt	1/4
Wheat flour	180
Vanilla extract	2 55

MORTIMER BYE.
